US00D516136S

(12) **United States Design Patent** (10) Patent No.: **US D516,136 S**
Yuen (45) Date of Patent: **** Feb. 28, 2006**

(54) **RADIO CONTROLLER FOR TOY AEROPLANE**

(75) Inventor: **Shun Ming Yuen**, Kowloon (HK)

(73) Assignee: **Golden Bright Manufacturer Ltd.**, Kowloon (HK)

(**) Term: **14 Years**

(21) Appl. No.: **29/208,770**

(22) Filed: **Jul. 2, 2004**

(30) **Foreign Application Priority Data**

Jan. 5, 2004 (HK) 0410023

(51) **LOC (8) Cl. 21-01**

(52) **U.S. Cl. D21/566**

(58) **Field of Classification Search** D21/266,

D21/324, 331, 333; D14/400, 401, 217, 218;
446/454-456; 463/6, 7, 37-39, 46, 47; D13/168

See application file for complete search history.

(57) **CLAIM**

The ornamental design for a radio controller for toy aeroplane, as shown and described.

DESCRIPTION

FIG. 1 is a front elevational view of a radio controller for toy aeroplane in accordance with my invention thereof;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view of a radio controller for toy aeroplane.

The word Tech.art forming part of the claimed design is a registered trademark of Golden Bright Manufacturer LTD.
